UNITED STATES PATENT OFFICE.

LUTHER ADDISON ELLISON, OF TOPEKA, KANSAS.

BURGLARPROOF SAFE.

Application filed June 17, 1924. Serial No. 720,587.

To all whom it may concern:

Be it known that I, LUTHER ADDISON ELLISON, a citizen of the United States, residing at Topeka, in the county of Shawnee and State of Kansas, have invented certain new and useful Improvements in Burglarproof Safes, of which the following is a specification, reference being had to the accompanying drawings.

This invention relates to an improved safe for use in a bank or other similar institution where large sums of money are kept on hand, and one object of the invention is to provide a safe in which the money may be kept in compartments provided in a rotating drum, and to provide improved means for imparting a very slow rotation to this drum so that the different compartments positioned about the drum may be successively brought into registry with an entrance to the chamber having the drum mounted therein.

Another object of the invention is to so construct the safe that the drum-turning means may be mounted in the compartment beneath the drum where it will be covered by the drum and prevented from being tampered with so that the drum may be caused to rotate faster than desired. It is desired to have this drum rotate very slowly so that a relatively long length of time will be required to bring a filled compartment into position for removal of the money therefrom, thereby preventing removal of the money by robbers who would not have time to wait until the drum has rotated a sufficient amount to bring the compartments into position where access may be had to them.

Another object of the invention is to so construct this drum-turning mechanism that the main drive shaft therefor may be formed in two sections normally connected by a governor-controlled clutch which will cause one of the clutch members to be moved out of engagement with the other clutch member if the drive shaft is rotated at too fast a speed.

Another object of the invention is to so construct this drum-turning mechanism that it may be rotated through the medium of an electric motor having a switch, and to provide means for causing the switch to be turned off when the drive shaft and motor shaft have been rotated a sufficient number of revolutions to move a compartment of

the drum into position where access may be had to the contents thereof. 55

Another object of the invention is to so construct this safe that the motor may be mounted upon a support externally of the body portion of the safe and have its shaft releasably connected with the outer end of the main drive shaft of the drum-rotating mechanism, thereby permitting this motor to be removed for repair purposes when necessary. 60

This invention is illustrated in the accompanying drawings, wherein:—

Figure 1 is a view showing the improved safe in front elevation;

Figure 2 is a vertical sectional view 70 through the upper portion of the safe;

Figure 3 is an enlarged view in elevation showing the switch operating means;

Figure 4 is a view of the turn-button switch; 75

Figure 5 is an enlarged sectional view showing the governor construction;

Figure 6 is a horizontal sectional view 80 through the upper portion of the same;

Figure 7 is a sectional view through the 85 drum.

This improved safe is provided with a body portion, which is indicated in general by the numeral 1, and will be formed of very strong metal, such as steel or the like. 90 This body is provided with a base portion for resting upon a suitable support and, if desired, this base portion may be formed hollow so that money and other valuables may be placed in the base. Entrance is 95 gained to the interior of this base by an entrance having a closure door 2 which may be releasably held in a closed position by any desired means. The head 3 of this body is provided with an upper section 4 which is formed separate from the lower section 5 and will rest upon this lower section and be secured in place by hot metal poured into registering recesses formed in the contacting faces of the upper and lower sections and then allowed to cool, and provide the retaining keys 6. A chamber 7 is formed in the head 3 and extends from a point adjacent the lower end of the lower head-forming section 5 to a point intermediate the depth of the upper head-forming portion 4. Access to this chamber is had 100 through an opening or passageway 8 provided with a closure door 9 which may be

105

securely locked, when so desired, by any suitable locking means. It will thus be seen that this safe is provided with a very strong body portion and that it will be very difficult 5 to obtain access to the chamber 7 formed in the head 3 when the door 9 is closed.

The money which it is desired to protect is to be placed in compartments 10 positioned about the circumference of the drum 11, and each of these compartments will be provided with a closure door 12 which is hingedly mounted and may be provided with locks 13 as an additional protection against removal of the money or other valuables from the compartments 10. It will be further noted that one of the compartments may be provided with a flooring plate 14 removably held in place so that when it is desired to inspect the turning mechanism 15 located beneath this drum, the compartment having the removable flooring may be moved to a position in registry with the entrance 8 and the door of this compartment then 20 opened so that the flooring may be removed 25 and drawn outwardly through the entrance 8. Of course, if so desired, each of the compartments may be provided with a removable flooring plate, but this is not necessary.

This drum is positioned within the chamber 7 and is rotatably carried by a shaft 15 extending vertically in the compartment 7 and axially through the drum with its upper end portion fitting into a socket 16 formed 30 in the upper section 4 of the casing head and 35 its lower end portion fitting into a socket 17 formed in the lower portion of the casing or body portion of the safe. It will, of course, be obvious that if desired separate shafts could be provided instead of a single shaft, 40 with one shaft extending upwardly from the top of the drum and the other extending downwardly from the lower end of the drum.

The drum is rotatably mounted upon this 45 shaft 15 and has its lower head provided with a depending neck portion 18 positioned above the upwardly extending hub portion 19 of a large worm gear 20 which rotatably fits upon the shaft 15 in the bottom of the chamber 7. Bearing balls 21 are provided 50 between the neck 18 and upper end of the hub 19 so that the drum may turn easily, and similar bearing balls 22 are provided 55 between the hub of the worm wheel 20 and the bottom of the chamber 7 so that thus the worm wheel can turn freely at a different rate of speed from that of the drum.

In order to transmit rotary movement 60 from the worm wheel 20 to the drum, there has been provided a short shaft 23 rotatably mounted in a bearing 24 extending over the worm wheel from the bottom portion of the chamber 7, and this shaft 23 carries at one 65 end a skew gear 25 and at its other end a worm 26. The worm 26 meshes with de-

pending teeth 27 formed about the lower head of the drum and the skew gear is engaged by a worm thread 28 extending upwardly from the upper face of the worm wheel 20. It will thus be seen that each 70 time the worm wheel 20 makes a complete revolution, the skew gear 25 and shaft 23 will be turned a portion of a rotation corresponding to one tooth of the skew gear 25, and that each time the shaft 23 makes a 75 complete revolution the worm 26 will impart rotary movement to the drum an amount corresponding to one of the teeth 27. Therefore, the drum rotates at a greatly reduced rate of speed when compared to the 80 speed at which the worm wheel 20 rotates.

In order to impart rotary movement to the worm wheel 20, there has been provided a main drive shaft having end sections 29 and 30. The outer shaft section 29 is projected into the chamber 7 through a bearing opening 31 formed in the wall of the lower head-forming section 5 and at its outer end this shaft section 29 is provided with an enlarged circular head 32 fitting into a pocket 33 formed about the outer end portion of the opening 31. The inner end of this shaft is threaded and carries a collar 34 which is screwed upon the shaft 29 a sufficient distance to prevent the shaft from having longitudinal play in the opening 31 and secured in the desired position upon the threaded end portion of the shaft by means of a set screw 35. The collar 34 is provided with teeth 36 upon its exposed end face and, therefore, this collar will provide a clutch section for engagement by the teeth of the governor operated clutch section or collar 37 slidably mounted upon the shaft section 30 and held against rotation upon this shaft 100 section 30 by the key 38. The end of the shaft section 30 fits into the portion of the clutch member 34 which extends beyond the threaded end of the shaft section 29 and, therefore, these shaft sections will be held 110 in axial alignment with each other. The clutch member 37 forms a portion of a motor which includes the clutch member or collar 37, a second collar or ring 39 which rotatably fits upon a sleeve 40 carried by the 115 shaft 39, and spring arms 41 extending between and secured to the collars 37 and 39 and carrying weights 42 which will be thrown outwardly by centrifugal force set up when the shaft section 30 is rotating at 120 too great a speed and will cause the clutch member 37 to be drawn away from the clutch section 34. This will cause the shaft 30 to be disconnected from the shaft section 29 and, therefore, a rotation of this shaft section 30 will be prevented when necessary. The inner end of the shaft section 30 is rotatably mounted in a bearing 43 positioned in the bottom of the chamber 7, and adjacent this bearing 43 there has been provided 130

a worm 44 which engages with the teeth of the worm wheel 20 and will impart rotary movement to this worm wheel at a slower speed than the speed at which the main 5 drive shaft is rotated.

In order to impart rotary movement to the main drive shaft, there has been provided an electrically operated motor 45 which will be of a conventional construction 10 and will be mounted upon a bracket 46 extending from the body of the safe. The shaft 47 of this motor carries a head 48 and this head 48 will be releasably connected with the head 32 of the outer shaft section 15 29 by removable fasteners 49 or in any other desired manner which will permit of its being disconnected from the head 32 when it is desired to remove the motor and make suitable repairs or replace it with a new 20 motor. A control switch 50 of the turn-button type is provided for this motor and will preferably be mounted upon a supporting shelf or bracket 51 secured to the body of the motor and extending beneath the 25 motor shaft 47. It is desired to have this turn-button switch moved to an off position when the drum has been rotated a sufficient distance to move a filled compartment of the drum into registry with the entrance opening 30 in the head of the body of the safe and there has, therefore, been provided the following mechanism which will cause this switch to be automatically shut off, thereby making it only necessary to manually turn 35 the switch to an on position and then let the motor run until the switch is automatically moved to an off position.

In order to permit of this switch being moved to an off position, the motor shaft 40 47 has been provided with a worm 52 which is enclosed by the upwardly extending portion 53 of a casing 54, the lower end of which is secured to the bracket or shelf 51. This casing 54 will be preferably formed of 45 separable side sections releasably held together by removable fasteners so that when desired the casing may be taken apart. Within the casing 54 there has been provided a worm wheel 55 which is rotatably 50 mounted, as shown at 56, and has its teeth engaged with the worm 52 so that each time the shaft 47 makes a complete revolution the worm wheel will be rotated a distance of one tooth. In addition to being provided 55 with the teeth for engagement by the worm 52, this worm wheel has also been provided with a worm thread 57 upon one side and having engagement with the teeth of the 60 worm wheel 58 which is rotatably mounted in the casing 54 at right angles to the worm wheel 55. It will, therefore, be seen that each time the worm wheel 55 makes a complete revolution the worm wheel 58 and the shaft 59 which carries this worm wheel and 65 is rotatably mounted in the bearing sleeve

60 will be rotated a distance corresponding to one tooth of the worm wheel 58. The shaft 59 which carries the worm wheel 58 extends out of the sleeve 60 and carries an arm 61 which extends radially of the shaft 70 59 and is of sufficient length to engage the operating head or button 62 of the turn-button switch 50.

It will be readily seen that after the turn-button switch has been turned to an on position, the motor will continue to operate 75 and impart rotary movement to the drum until the shaft 59 has made a complete revolution to bring the abutment arm 61 into engagement with the knob 62 of the turn-button switch and move this knob to turn the switch to an off position. The flow of current to the motor will then, of course, be cut off and the motor will cease to operate until the turn-button switch is again 80 moved to the on position. It will thus be seen that when the supply of money in use is running low, it is only necessary for the paying teller of a bank to turn the button 62 so that the motor will be put in motion and 85 the drum caused to slowly rotate. The drum will then be caused to rotate until a filled compartment has been moved into position where access may be had to it through the entrance passage 8 in the head of the safe, 90 at which time the button will be turned to the off position and operation of the motor stopped. The door 12 of the compartment can then be opened and the cash can be removed from this compartment as needed. 100

From the above description, it will be seen that there has been provided a safe in which a large supply of money can be kept in separate compartments and the major portion of this money protected so that access may not be had to it. This will, therefore, prevent daylight robbers obtaining any money except the money in actual use, as a daylight robber would not have time to wait until the drum had been slowly turned into position to bring the filled compartments into registry with the entrance to the safe. It will be further noted that even if the compartment having the removable bottom plate were positioned in operative relation to the entrance and the bottom plate removed, the various gears and shafts positioned beneath the drum could not be readily forced out of proper engagement with each other and, therefore, it would be impossible to release 110 the drum and permit of its being freely rotated.

It will be further noted that removal of the motor would also not be of any help, as 115 it is necessary to impart rotary movement to the drive shaft in order to rotate the drum, and further the embedded head of the outer drive shaft section would prevent the shaft from being readily pried out and, therefore, an explosive could not be passed into the 120 125 130

opening 31 in which this outer drive shaft section is rotatably mounted.

I claim:—

1. A safe comprising a body having a chamber provided therein, a drum rotatably mounted in said chamber having compartments successively moving into registry with the entrance to the chamber as the drum is rotated in the chamber, means for imparting rotary movement to said drum including a main drive shaft, an electrically operated motor for imparting rotary movement to said shaft, and a control switch for said motor, and means for moving said switch to an off position after said shaft has been rotated a predetermined number of times and the drum rotated a sufficient amount to move a compartment thereof out of registry with the entrance to the chamber and another compartment into registry with the entrance.

2. The structure of claim 1 having the shaft of the motor secured to the drive shaft of the drum-turning means and the switch operating means actuated from the motor shaft and including a rotatable shaft carrying a radially extending abutment for engaging and moving the switch to an off position during rotation of the shaft.

3. A safe comprising a body having a chamber therein and provided with an entrance, a drum rotatably mounted in said chamber, means for imparting rotary movement to said drum for successively moving compartments provided about the drum into registry with said entrance, said means including a rotatably mounted drive shaft formed in two portions, means for transmitting rotary movement from the drive shaft to the drum at a reduced rate of speed, and means for preventing rotation of a portion of the drive shaft when the drive shaft is rotated at too high a speed.

4. The structure of claim 3 having the drive shaft formed in sections in end to end relation to each other, a clutch member carried by one shaft section, and a spring governor carried by the other shaft section and including a clutch member keyed thereto for longitudinal sliding movement into and out of operative engagement with the clutch member of the first mentioned shaft section.

5. The structure of claim 3 having the drive shaft formed in sections in end to end relation to each other, a clutch member carried by one shaft section, a spring governor carried by the other shaft section and including a clutch member keyed thereto for longitudinal sliding movement into and out of operative engagement with the clutch member of the first mentioned shaft section, a collar adjustable longitudinally upon the second mentioned shaft section, a ring rotatable upon said collar, and weight carrying spring arms extending between and se-

cured to the ring and last mentioned clutch section.

6. A safe comprising a body having a chamber formed therein and an entrance to the chamber, a drum in said chamber having compartments to be brought into registry with the entrance to the chamber, a shaft rotatably mounted in said drum, a worm wheel rotatably mounted upon said shaft beneath the drum and having a worm thread extending from its upper face, said drum being provided with depending gear teeth, a shaft rotatably mounted between the worm wheel and drum and having at one end a worm gear engaged by the worm thread of the worm wheel and at its other end having a worm meshing with the teeth of said drum, a driving shaft rotatably mounted in said chamber and having a worm meshing with the teeth of said worm wheel, said drive shaft extending externally of the body of said safe for connection with means for rotating the drive shaft.

7. A safe comprising a body having a chamber therein and an entrance to the chamber, a drum rotatably mounted in said chamber and having compartments successively moving into position for access through the entrance when the drum is rotated, means for imparting rotary movement to said drum, said means including a drive shaft having an outer section journaled in the wall of the body and an inner section rotatably mounted in the chamber, a head upon the outer end portion of the outer shaft section, a collar screwed upon the inner end portion of the outer shaft section to hold the outer shaft section against longitudinal movement and extending inwardly beyond the inner end of the outer shaft section and rotatably receiving one end of the inner shaft section, said collar having its exposed face provided with clutch teeth, a sleeve mounted upon the inner shaft section and adjustable longitudinally thereon, a governor having a collar rotatably mounted upon said sleeve, a second collar keyed to the inner shaft section for movement longitudinally thereof and having clutch teeth for engaging the clutch teeth of the collar upon the outer shaft section, and weight-carrying spring arms extending between and connected with the collars carried by the inner shaft section to draw the last mentioned shaft collar out of engagement with the collar of the outer shaft section when the drive shaft is rotating beyond a predetermined rate of speed.

8. A safe comprising a body having a chamber formed therein and an entrance to the chamber, a drum rotatably mounted in said chamber and having compartments movable into registry with the entrance when the drum is rotated, means for impart-

- ing rotary movement to the drum includ-
ing a drive shaft rotatably mounted and ex-
tending externally of the body, means in the
chamber for transmitting rotary movement
5 from the drive shaft to the drum, an oper-
ating motor having a motor shaft connected
with the outer end of the drive shaft, a
control switch, a train of gearing rotated
from the motor shaft and including a ro-
10 tatably mounted gear-carrying shaft, and an
abutment arm carried by said gear-carrying
shaft for engaging the switch and moving
the switch to an off position as the said gear-
carrying shaft rotates.
- 15 9. A safe comprising a body having a
chamber therein and an entrance to the
chamber, a drum rotatably mounted in the
chamber and having compartment about its
periphery movable into registry with the
20 entrance, means for imparting rotary move-
ment to the drum including a train of gear-
ing in the chamber having operative con-
nection with the drum, a drive shaft ex-
tending externally of the body, a motor hav-
25 ing a motor shaft connected with the drive
shaft, a control switch for said motor and
including a rotatable actuating element,
means actuated from the motor shaft for im-
parting movement to the turnable operat-
30 ing element of said switch, said means com-
prising a casing having a portion thereof
positioned about the motor shaft, a worm
carried by the motor shaft within the casing,
a driven shaft journaled in the wall of the
35 casing and extending externally thereof, an
abutment arm carried by and extending
radially of the outer end portion of said
shaft, a train of gearing in said casing in-
cluding a worm gear meshing with the worm
40 upon said motor shaft, and a gear carried by
the inner end portion of the shaft having the
abutment carried thereby.
10. A safe comprising a body having a
chamber therein provided with an entrance
and a door therefor, a drum rotatably 45
mounted in said chamber and having an en-
trance door adapted to be brought into regis-
try with the entrance to the body, means
for imparting rotary motion to the drum
including a motor exterior to the body, and 50
manually operable means for controlling
said motor.
11. A safe comprising a body having a
chamber therein, the body being provided
with an entrance and a door therefor, a 55
drum rotatably mounted in said chamber
and having a door adapted to register with
the door in the body, means for imparting
slow rotary movement to said drum includ-
ing a rotatable member having a spiral 60
thread upon its face, a skew gear with which
said spiral thread engages, the skew gear
being operatively engaged with the drum to
rotate the same, and means exterior to the
body for driving the rotatable member at a 65
relatively slow rate of speed.
12. A safe comprising a body having a
chamber therein, the body being provided
with an entrance having a door, a drum fit-
ting said chamber and rotatably mounted 70
therein and having a plurality of compart-
ments, the compartments being adapted to
be brought successively into registry with
the entrance in the body, means for rotating
the drum including an electrically actuated 75
motor disposed in circuit with a source of
energy and a switch, and means for moving
said switch to an off position to break the
circuit between the motor and the source of
current after the drum has been rotated a 80
predetermined amount to bring a compart-
ment thereof into registry with the entrance
opening in the body to thereby stop the
movement of the drum.

In testimony whereof I hereunto affix my 85
signature.

LUTHER ADDISON ELLISON.
